UNITED STATES PATENT OFFICE.

GEORGE L. CAMPBELL, OF SPRINGFIELD, MISSOURI.

UNION-OVERALLS.

1,341,224.

Specification of Letters Patent. Patented May 25, 1920.

Application filed November 3, 1919. Serial No. 335,314.

To all whom it may concern:

Be it known that I, GEORGE L. CAMPBELL, a citizen of the United States, residing at Springfield, in the county of Greene and State of Missouri, have invented certain new and useful Improvements in Union-Overalls; and I do hereby declare the following to be a full, clear, and exact description of the invention, such as will enable others skilled in the art to which it appertains to make and use the same.

My invention relates to overalls, and is an improvement in men's union overalls that is in bifurcated one piece or union garments.

My invention consists in providing a means whereby additional strength and appearance are given to the garment and the garment is made more durable and attractive.

My invention relates to union overalls provided with a drop seat, and relates to a part whereby the row of buttons along the upper or blouse part, to which this drop seat is buttoned, are concealed, and which adds to the strength of the garment and to the comfort of the wearer by performing also the functions of a belt.

I have shown my invention in the accompanying drawing, in which:

Figure 1 is a three-quarter front view of the entire garment buttoned upon a wearer;

Fig. 2 is a rear view showing the garment completely buttoned with the rear buttons indicated in dotted lines;

Fig. 3 is a rear view with the curtain which forms a feature of my device lifted and the belt unfastened; and

Fig. 4 is a side view of the parts shown in Fig. 3.

In the drawings, 1 represents a complete suit of overalls. In the rear I provide a drop seat or sanitary flap 2 adapted to be buttoned to the upper or blouse part 3 by a row of buttons 4 secured to the part 3.

Immediately above this row of buttons I stitch a short or narrow curtain 5 by a seam 6, said seam extending across the back. At the end of said seam I provide an extra or strengthening row or bunch of stitching

forming a stay 7, to prevent the belt or curtain from being ripped off. The curtain is of a width to conceal conveniently the row 4 of buttons, and this is about the proper width for a belt.

The ends of the curtain are continued forward from the stayed points, as a belt.

This belt is provided with button holes 8, 8, which may serve to attach it to buttons 9, 9, at the front when the belt or curtain is turned down to proper position, or for adjustment. The front ends are left free in the sense that they are attached by no seam along an edge. Other securing means may be provided, of course.

My curtain is a belt of doubled material preferably, fully stitched throughout its length and attached in its middle portion by its upper edge, just above the row of buttons 4, the buttons not appearing when the garment is fully in place on the wearer's person. The blouse and drop seam are each fully finished with a hem preferably.

It will thus be seen that I have devised a convenient, sightly, durable and novel garment, one which appeals to the esthetic as well as practical sense of the average man whose occupation entails the constant use of overalls. The belt or curtain strengthens the waistband of the blouse and takes some strain of the waistband of the drop seat.

Having thus described my invention what I claim as new and desire to secure by Letters Patent of the United States, is:

1. In a union garment provided with a drop seat, there being buttonholes in the waistband thereof, buttons on the blouse part, and, in combination therewith a curtain stitched to said blouse part immediately above said buttons by its upper edge across the back, said curtain being of a width merely sufficient to conceal said buttons, and being prolonged as free ends so as to come to the front of the wearer and give the appearance of a belt, said belt being provided with stays where the free ends begin, and securing means for said belt.

2. In a union garment provided with a drop seat, there being buttonholes in the waistband thereof, buttons on the blouse part, and, in combination therewith a curtain stitched to said blouse part immediately above said buttons by its upper edge across the back, said curtain being of a width merely sufficient to cover said buttons and give the appearance of a belt, being attached at its upper edge across the back only, stays attaching it at the ends of the rear seam, said belt being continued as free ends from the stays, so as to form a belt, there being attached to the front of the blouse securing means for said belt,

3. A bifurcated union body garment, provided with a drop seat, buttonable to the blouse part, a row of buttons on the waist line of said blouse part, and a belt stitched to said blouse part by a line of stitching along its upper edge just above the buttons across the back, stays at the ends of said

stitching, said belt being adapted to extend forward, the front ends being free, and means for fastening it in front.

In testimony whereof, I affix my signature. ¹⁰

GEORGE L. CAMPBELL.
